UNITED STATES PATENT OFFICE.

SAMUEL B. SKLAR, OF MINNEAPOLIS, MINNESOTA.

DESIGN FOR A SMOKER'S CABINET.

Application filed October 27, 1927. Serial No. 23,903. Term of patent 7 years.

To all whom it may concern:

Be it known that I, SAMUEL B. SKLAR, a citizen of the United States, residing at Minneapolis, in the county of Hennepin and State of Minnesota, have invented a new, original, and ornamental Design for a Smoker's Cabinet, of which the following is a specification, reference being had to the accompanying drawing, forming part thereof.

Figs. 1 and 2 are perspective views of the opposite sides and ends of a smoker's cabinet, showing my new design.

I claim:

The ornamental design for a smoker's cabinet, as shown.

SAMUEL B. SKLAR.
